SKI FASTENER

Hans Jensen, Sarpsborg, Norway

Application November 3, 1932, Serial No. 641,073,
and in Norway February 20, 1931

5 Claims. (Cl. 208—184)

This invention relates to ski fasteners of the kind in which the sole of the boot is secured to the ski by means of an eccentric device mounted in the toe clamping iron. The invention differs 5 from the hitherto known devices of this kind in that the eccentric itself in combination with a covering secured to the sole of the boot serves as clamping member, the covering being so formed that the eccentric, in addition to pressing down the sole of the boot against the ski, also causes the sole to be moved forward a small amount in the toe irons and fixed in this position.

A constructional example of the invention is 15 illustrated in the drawing.

Fig. 1 shows a toe clamping iron seen from the inside with a part of a sole with applied covering in cross-section on the line A—A of Fig. 3 in the position before being fastened.

20 Fig. 2 corresponds to the arrangement shown in Fig. 1, the sole of the boot has been secured.

Fig. 3 is a plan view of the toe clamping iron turned through 90° with respect to Fig. 2.

Fig. 4 shows a part of a boot with a covering 25 applied in side elevation.

Fig. 5 shows the boot covering in cross-section on the line B—B of Fig. 4.

1 is a toe clamping iron of any known construction in which a pin 2 is rotatably mounted 30 which is made in one piece with a circular eccentric 3 arranged eccentrically on the inner side of the toe clamping iron and intended for bearing against a covering 4 on the edge of the sole 5 of the boot. The part of the pin 2 projecting outside the toe iron 1 is formed with a four-sided part for receiving a lever 6, which, by means of a screw nut 7, is secured to the end of the pin which is threaded. Near the free end the lever 6 is provided with a locking pin 8 which, when the 35 lever is pressed down, is brought into engagement with one of the holes 9 of a series provided in the toe clamping iron and thereby secures the lever in position. In order to obtain reliable engagement of the locking pin 8 in one of the 40 holes 9 and at the same time to secure it, the lever 6 is made somewhat resilient so that it is always kept pressed against the outside of the toe iron. The covering 4 secured to the edge of the sole of the boot has an L-shaped section 45 and its upper surface has a raised part 10 intended to co-operate with the eccentric 3 when the latter is depressed during the fastening of the boot. At each end the covering 4 is formed with a projecting point 11 which together with the screw 12 ensures reliable fixing of the covering to the edge of the sole.

When the boot is to be fastened on, the lever 6 is first moved upwards (compare Fig. 1) so that the raised part 10 of the covering 4 secured 55 to the sole 5 can pass freely under the eccen-

tric 3 when the boot is pushed in between the toe irons. Then the lever 6 is moved downwards whereby the eccentric 3 bears against the raised part 10 on the covering 4 and causes the boot to be moved forward slightly so that it is tightly fixed between the toe irons and at the same time is pressed against the ski. In this position, which is illustrated in Fig. 2, the lever 6 is fastened by the bolt 8 being brought into engagement with the nearest hole 9 of the row of holes 70 in the toe iron 1. As is clear from the drawing, the boot is then held rigidly and securely.

What I claim is:

1. A ski fastener having toe clamping irons, eccentric devices mounted on each of the toe 75 clamping irons, and coverings secured to the sole of the boot and adapted to co-operate with the eccentric devices, the coverings being of such shape that the eccentric when rotated for fastening, in addition to pressing the covering with the sole against the bottom plate of the toe iron, also causes the sole to be moved forward between the toe irons.

2. A ski fastener having toe clamping irons, eccentric devices mounted on each toe fastening 80 iron, a covering secured to the sole of the boot and adapted to co-operate with the eccentric devices, and a raised part on the said covering which can pass under the eccentric device in the raised position thereof and against which the eccentric device bears when depressed so as to move the boot forward and press it downwards against the toe iron.

3. A ski fastener having toe clamping irons, eccentric devices on the toe clamping irons, and a covering secured to the sole of the boot and adapted to co-operate with the eccentric device for securing the boot and moving it forward between the toe irons, the covering being of L-shaped section and having at its ends projecting 95 points which, when the covering is screwed to the sole, are forced into the sole and ensure satisfactory fixing.

4. A ski fastener having toe clamping irons, eccentric devices mounted on the toe clamping 105 irons, a covering secured to the sole of the boot and adapted to co-operate with the eccentric for securing the boot, a lever for turning the eccentric and a bolt on the lever engaging with perforations provided in the toe iron for holding the eccentric 110 in position.

5. A ski fastener as claimed in claim 4, in which the lever bears resiliently against the outer side of the toe iron.

HANS JENSEN. 115
